UNITED STATES PATENT OFFICE.

GEORGE W. COPE AND WILLIAM L. BERTRAM, OF DETROIT, MICHIGAN, AS-SIGNORS TO KALAMAZOO STOVE COMPANY, OF KALAMAZOO, MICHIGAN.

DESIGN FOR A RANGE.

SPECIFICATION forming part of Design No. 36,311, dated May 5, 1903.

Application filed October 4, 1902. Serial No. 125,992. Term of patent 7 years.

To all whom it may concern:

Be it known that we, GEORGE W. COPE and WILLIAM L. BERTRAM, citizens of the United States, residing at the city of Detroit, in the county of Wayne and State of Michigan, have invented a new, original, and ornamental Design for a Range, of which the following is a specification.

Our new and ornamental design for a range is shown in the accompanying perspective drawing.

The leading and material features of our design is in the novel and ornamental figures produced thereon.

A subordinate feature is the ornamental shape of the range with which such figures are combined.

Referring to the drawing, the base of the range is ornamented by bold scroll figures, which are arranged in opposite directions from a central double figure, with which they are linked or entwined. The lower edge of the base is conformed to the figures and the figures are continued onto the legs which are conformed thereto.

In the center of the oven-door is a fluted rosette resting upon an oval-shaped figure having inwardly and upwardly curved projecting scrolls. About the door is a fluted

border portion, which is further ornamented by a bold scrollwork corresponding in general effect to the scrollwork of the base.

On the fire-box door is an open scroll design which, with its divisions, covers substantially the entire surface. Below the door on the fire-box plate is a similar bold scrollwork design. This same general idea of heavy-shaped scrollwork is carried out upon the front of the stove, which is in a measure conformed thereto.

On the reservoir-plate are fanciful C-shaped ribs or scrolls of varying sizes, which are interwoven or linked together. The bottom of the reservoir is conformed to said scrolls.

Having thus described our invention, what we claim as new, and desire to secure by Letters Patent, is—

The ornamental design for a range, substantially as herein shown and described.

In witness whereof we have hereunto set our hands and seals in the presence of two witnesses.

GEORGE W. COPE. [L. S.]
WILLIAM L. BERTRAM. [L. S.]
